UNITED STATES PATENT OFFICE.

WILLIAM W. GLECKNER, OF CANTON, PENNSYLVANIA.

CHECK-LOOP.

No. 824,005.

Specification of Letters Patent.

Patented June 19, 1906.

Application filed February 1, 1906. Serial No. 299,040.

To all whom it may concern:

Be it known that I, WILLIAM W. GLECKNER, a citizen of the United States, residing at Canton, in the county of Bradford and State of Pennsylvania, have invented certain new and useful Improvements in Check-Loops; and I do declare the following to be a full, clear, and exact description of the invention, such as will enable others skilled in the art to which it appertains to make and use the same.

My invention relates to improvements in check-loops; and it consists in the novel construction, combination, and arrangement of parts hereinafter described and claimed.

The object of the invention is to provide a device of this character which will be of simple, durable, and comparatively inexpensive construction and well adapted for the purpose intended.

The above and other objects, which will appear as the nature of the invention is better understood, are accomplished by means of the construction illustrated in the accompanying drawings, in which—

Figure 1 is a view showing the application of my improved check-loop to an overdrawn check. Fig. 2 is a perspective view of the device, on an enlarged scale. Figs. 3 and 4 are respectively longitudinal and transverse sectional views through the same. Fig. 5 is a plan view of the strip of leather or similar material from which the loop is made, and Fig. 6 is a perspective view of a slightly-modified form of the invention.

Referring to the drawings by numeral, 1 denotes the usual checkrein or overdraw, 2 the usual saddle-hook or checkrein-hook, and 3 my improved check loop or holder. The latter consists of an eye 4 and a loop 5 of leather or other suitable material. The eye 4 may be in the form of a metal ring, as shown, in the form of a **D**, or of any other suitable form and construction. The loop 5 consists of a strip of leather or flexible material which is formed adjacent to its ends with openings 6 and which is slotted longitudinally, as at 7, between said openings or apertures, as clearly shown in Fig. 5 of the drawings. The openings or apertures 6 are provided to receive the ring or eye 4, and the slit 7 is provided to permit of the insertion of the ring or eye in said openings 6 after the strip has been bent upon itself to form the loop. The ring or eye is adapted to be retained in the openings 6 by means of a band

8, which surrounds the loop, as shown. This band 8 is preferably formed of a strip of leather which has its ends united by a metal fastener 9, as seen in Fig. 4 of the drawings. 60

In using the device the loop 5 is engaged with the hook 2, and the overdraw or checkrein 1 is engaged with the ring or eye 4, as shown in Fig. 1. This construction permits the ring or eye 4 to turn or work freely in the holes of the leather, so that it moves with the overdraw, while the loop is stationary upon the hook 2.

In Fig. 6 of the drawings the eye 4 is in the form of a **D**, the straight portion of which is formed by a screw 10, which is adapted to pass through the apertures or openings 6 in the ends of the loop 5. When a **D** having a screw, rivet, or the like 8 of this form is employed, it will be seen that it will be unnecessary to slit the loop, as at 7, and that the band 8 will also be unnecessary.

From the foregoing description, taken in connection with the accompanying drawings, the construction, operation, and advantages 80 of the invention will be readily understood without requiring a more extended explanation.

Various changes in the form, proportion, and the minor details of construction may be resorted to without departing from the principle or sacrificing any of the advantages of the invention as defined by the appended claims.

Having thus described my invention, what 90 I claim as new, and desire to secure by Letters Patent, is—

1. A device of the character described, comprising an eye, and a loop formed by a strip of flexible material slit longitudinally 95 between apertures in its ends to permit of the insertion of said eye in said apertures, substantially as described.

2. A device of the character described, comprising an eye, a loop formed by a strip 100 of flexible material slit longitudinally between apertures in its ends to permit of the insertion of said eye in said apertures, and means for retaining said eye in said apertures.

3. A device of the character described, comprising an eye, a loop formed by a strip of flexible material slit longitudinally between apertures in its ends to permit of the insertion of said eye in said apertures, and a band surrounding said loop for retaining said 105 eye in said apertures.

4. A check-loop comprising a ring and a

loop of leather formed with apertures adjacent to its ends to receive said ring and with a longitudinal slit between said apertures to permit of the insertion of said ring into said apertures, and a band surrounding said loop to retain said ring in said apertures, substantially as shown and described.

In testimony whereof I have hereunto set my hand in presence of two subscribing witnesses.

WILLIAM W. GLECKNER.
